Primary Examiner — Ian Simmons*Assistant Examiner* — Rashida C McCoy(74) Attorney, Agent, or Firm — Craig R. Miles; CR Miles P.C.CLAIM

I claim the ornamental design for a water shoe, as shown and described.

DESCRIPTION

FIG. 1 is a top and left side perspective of a water shoe, embodying my new design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines shown are included for the purpose of illustrating the unclaimed portions of the article and form no part of the claim.
